DRIP CATCHER FOR CONTAINERS

Irving E. Walker, Cranston, R. I.

Application June 8, 1938, Serial No. 212,546

2 Claims. (Cl. 65—31)

This invention relates to drip catchers for containers, and its general object is to provide a catcher that is primarily designed for use on pitchers and other pouring containers, for disposal below the pouring spout thereof to receive the normal drip of the contents of the container, which generally runs down the outside of the container to the bottom, and adheres to the latter, thereby wetting and soiling or staining the supporting surface of the container, when set thereon, but with the use of my catcher the bottom of the container is retained in a dry condition.

A further object is to provide a drip catcher that can be readily emptied, but leakage or casual removal or pouring of its contents therefrom is impossible, and the catcher can be easily and expeditiously cleaned and retained in a sanitary condition.

Another object is to provide a drip catcher of the character set forth, that is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a perspective view illustrating my drip catcher applied to a pitcher.

Figure 2 is a vertical sectional view taken through the pitcher and my drip catcher and illustrates the pitcher in pouring position.

Figure 3 is a vertical sectional view with the pitcher in normal position.

Referring to the drawing in detail, it will be noted that I have illustrated my drip catcher as being applied to a pitcher of a bowl type, but it can be applied to any type of pitcher as well as other pouring containers, such as tea pots, coffee pots, jugs and like vessels.

The pitcher as shown includes a body 1 and a pouring spout 2, and my drip catcher is secured to the body below the pouring spout, as shown, for the purpose of receiving the normal drip from the spout, and includes a substantially semi-cylindrical cup member 3 which is integral with the body or otherwise secured thereto, with the

open portion thereof uppermost to provide an inlet 4.

Due to the shape of the pitcher it will be noted that the cup member 3 is disposed at an upward inclination, and the member 3 has an open outer end, that is closed by a cap 5 that is threaded on the member 3 in the form as shown, the member being exteriorly threaded to receive the cap which has a gasket 6 mounted therein to provide a leakproof connection, as will be apparent.

The cap 5 includes an annular skirt 7, so that a portion of the skirt will overlie the inlet 4, as clearly shown in Figures 2 and 3 and thereby prevent the passage of the contents of the pocket 8 that is provided by the member 3 and cap 5, through the inlet, regardless of the angle the pitcher is held when pouring the contents of the pitcher therefrom, therefore it will be obvious that the entire contents of the pitcher can be poured without escape of the pocket contents.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A drip catcher for a container and comprising a substantially semi-cylindrical cup member secured to the body of the container with its open portion uppermost to provide an inlet, said member having an open outer end and being exteriorly threaded, a cap threadedly secured to said member for closing the outer end thereof and a skirt included in the cap and a portion of the skirt overlying the major portion of the inlet.

2. A drip catcher for a spouted container and comprising a substantially semi-cylindrical cup member secured to the body of the container with its open portion uppermost to provide an inlet disposed to underlie the spout of the container, said cup member having an open outer end and being exteriorly threaded, a cap including a skirt threaded on the cup member and having a portion overlying the inlet but spaced from the container, and a gasket in the cap to provide a leakproof connection between the cup member and the cap.

IRVING E. WALKER.
